CLAIM

The ornamental design for a multi-socket hub, as shown and described.

DESCRIPTION

FIG. 1 is a left, front, top, perspective view of a first embodiment of a multi-socket hub showing our new design. FIG. 2 is a right, front, bottom perspective view thereof. FIG. 3 is a front elevation view of the multi-socket hub of FIG. 1, shown somewhat enlarged.

FIG. 4 is a rear elevation view thereof.

FIG. 5 is a left side elevation view of the multi-socket hub of FIG. 1.

FIG. 6 is a right side elevation view thereof.

FIG. 7 is a top plan view thereof.

FIG. 8 is a bottom plan view thereof.

FIG. 9 is a left front top perspective view of a second embodiment of a multi-socket hub showing our new design.

FIG. 10 is a right front bottom perspective view thereof.

FIG. 11 is a front elevation view of the multi-socket hub of FIG. 9, shown somewhat enlarged.

FIG. 12 is a rear elevation view thereof.

FIG. 13 is a left side elevation view of the multi-socket hub of FIG. 9.

FIG. 14 is a right side elevation view thereof.

FIG. 15 is a top plan view thereof; and,

FIG. 16 is a bottom plan view thereof.

(Continued)

The equal-length broken lines in the drawings depict portions of the multi-socket hub that form no part of the claimed design. The dash-dot-dash lines define the boundaries of the claim.
